(57) CLAIM

The ornamental design for an aerial for doppler effect hyper frequency detector, as shown and described.

DESCRIPTION

FIG. 1 is a front view of a first embodiment of a aerial for doppler effect hyperfrequency detector.

FIG. 2 is a rear view of the FIG. 1 an aerial for doppler effect hyper frequency detector.

FIG. 3 is a left side view of the FIG. 1 aerial for doppler effect hyper frequency detector.

FIG. 4 is a right side view of the FIG. 1 an aerial for doppler effect hyper frequency detector.

FIG. 5 is a top view of the FIG. 1 an aerial for doppler effect hyper frequency detector.

FIG. 6 is a bottom view of the FIG. 1 an aerial for doppler effect hyper frequency detector.

FIG. 7 is a front view of a second embodiment of an aerial for doppler effect hyperfrequency detector.

FIG. 8 is a rear view of the FIG. 7 an aerial for doppler effect hyper frequency detector.

FIG. 9 is a left side view of the FIG. 7 an aerial for doppler effect hyper frequency detector.

FIG. 10 is a right side view of the FIG. 7 an aerial for doppler effect hyper frequency detector.

FIG. 11 is a top view of the FIG. 7 an aerial for doppler effect hyper frequency detector; and,

FIG. 12 is a bottom view of the FIG. 7 an aerial for doppler effect hyper frequency detector.
